ENGINE

Andre J. Meyer, Detroit, Mich., assignor to Continental Motors Corporation, Detroit, Mich., a corporation of Virginia

Application April 27, 1931. Serial No. 533,091

16 Claims. (Cl. 123—81)

My invention relates to internal combustion engines and more particularly to the engine structure and means for efficiently assembling various cooperating engine elements together. In particular my invention is especially adapted for use with a sleeve valve engine in which the sleeve valve means are preferably assembled through the bottom of the engine cylinder.

One of the difficult problems encountered in constructing an engine of the sleeve valve type is to provide a structure of minimum over-all length so as to provide an engine which is not of such a length as to prohibit its practical application in an industry where minimum weights and dimensions are quite essential. It has been found that in general, engines of the sleeve valve type are considerably longer and more bulky than engines of the poppet valve type of the same power. This is due primarily to the necessity of providing sleeve valve means of a diameter in excess of the cylinder bore of a poppet valve engine and also to the fact that the means connecting the sleeve valve means with the sleeve driving mechanism necessitates the provision of sufficient clearance between cooperating engine elements in order to obtain an engine that can be operated satisfactorily.

One of the objects of my present invention is to construct an engine of the sleeve valve type of minimum dimensions thereby providing a compact engine structure comparable in weight and size with other types of engines.

Another object of my present invention is to facilitate the assembly of cooperating engine elements with minimumly spaced cylinders.

For a more detailed understanding of my invention, reference may be had to the accompanying drawings which illustrate one form which my invention may assume, and in which:

40 Figure 1 is a bottom plan view of a multi-cylinder engine constructed in accordance with my invention and showing parts broken away to illustrate the various steps in assembling the cooperating engine elements together;

45 Figure 2 is a longitudinal vertical sectional view of a portion of the engine illustrated in Figure 1 and taken substantially on the line 2—2 of Figure 1;

50 Figure 3 is a detail sectional view of a portion of the engine illustrating in detail the engine and sleeve construction permitting the axial assembly of said sleeve with the cylinder associated therewith, and

55 Figures 4, 5 and 6 are elevational views of the lower end of a single sleeve valve constructed in

accordance with my invention and Figure 7 is a detail sectional view taken substantially on the line 7—7 of Figure 5.

Preferably I have illustrated my invention as being incorporated in an engine of the sleeve valve type, the principle of my invention permitting the ready assembly of the sleeve valve means although obviously other engine elements such as pistons may be assembled with an engine in a manner as taught by this application. 60 In general an engine of the type herein illustrated comprises a cylinder block 10 provided with a plurality of cylinders 11. Suitable cylinder head structures 12 are secured to the cylinder block and are preferably provided with 65 portions 13 depending within the cylinder and spaced therefrom to provide sleeve pockets respectively adapted to receive the upper end of the sleeve valve means 15. Pistons 16 operate within the sleeve valve means and are preferably connected with the crankshaft 17 by means of the connecting rods 18.

The crankshaft 17 is adapted to be supported in suitable bearings 19 and 20 carried by the engine structure and in accordance with the accepted engineering practice I have provided such bearings at the ends of the crankcase and also intermediate the ends. Preferably the bearings 19 are located at the end of the engine structure and the bearings 20 are located intermediate 70 the end bearings and preferably intermediate a 75 pair of adjacent cylinders.

The bearings for supporting the crankshaft must be of sufficient length to carry the loads and under ordinary conditions said bearings 80 limit the distance permissible between adjacent cylinders and the distance between the end cylinder and end of the engine block, since it is generally necessary to assemble the sleeve valve means from the bottom of the cylinder due to 85 the fact that the lower or inner end of certain sleeve valve means are provided with an enlarged collar portion 21.

It will thus be noted that the sleeve valve means must clear the bearing structures if the same is to be assembled axially of the cylinder from below. I have discovered that by cutting out a portion of the bearing structures that the cylinders may be placed considerably closer together and in a multi-cylinder engine such as 100 herein illustrated the cylinders are minimumly spaced thereby producing a compact engine structure which is approximately the same length as a poppet valve engine of the same power. 105 This construction is made possible by recessing 110

the bearings to provide clearance between the bearing and sleeve valve means. It will be noted that the end portions of the bearing are formed with an arcuate recess of sufficient depth to provide clearance between the body portion 15' of the sleeve and the bearing structure. Figures 1 and 3 illustrate in a clear way how this sleeve valve means may be inserted axially into the cylinder past the bearing 20.

10. The collar portion 21 of the sleeve valve means is considerably thicker or larger in diameter than the body portion of said sleeve valve means and in order to pass the enlarged collar portion by the bearing the said collar portion is cut out 15 as at 22. A sleeve driving lug 23 is adapted to be secured in any suitable manner to the enlarged collar portion secured to the inner end of the sleeve valve means and preferably the sleeve driving lug is positioned diametrically 20 opposite the cut-out portion 22. On initially assembling the sleeve valve means with the engine the same is inserted in such a manner as to align the cut-out portion 22 of the sleeve with the bearing and when the sleeve has passed beyond the bearing the same may be partially rotated to bring the sleeve driving lug in a position where the same may be operatively connected with the sleeve driving mechanism which in the present instance consists of an arm or 25 other suitable connection 24 which is actuated by means of a wobble shaft 25.

It is noted that the construction herein illustrated permits the construction of a compact sleeve valve engine with minimumly spaced cylinders and one advantage of a construction as herein described and illustrated is that it materially aids in maintaining low production costs for engines of this character. This construction also facilitates the assembly of an engine of 30 this character with a minimum of time and labor and such a construction also materially aids in keeping maintenance costs and other operating costs at a minimum.

Although I have illustrated but one form of 45 my invention and have described in detail but a single application thereof, it will be apparent to those skilled in the art to which my invention pertains that various modifications and changes may be made therein without departing 50 from the spirit of my invention or from the scope of the appended claims.

What I claim as my invention is:

1. In an engine having a cylinder adapted for receiving a cooperating engine element, said engine provided with a bearing structure having a recessed portion providing clearance between the element and bearing structure on assembling said element with the engine cylinder.

2. In an engine having a cylinder adapted for receiving a cooperating engine element, said engine provided with a bearing structure having a recessed end portion providing clearance between the element and bearing structure on assembling said element with the engine cylinder.

65. 3. An engine structure having a cylinder adapted for receiving a cooperating engine element, a crankshaft, said engine structure provided with a crankshaft bearing having a recessed portion adapted to provide clearance permitting axial assembly of said engine element with said cylinder.

70. 4. An engine structure having a plurality of cylinders each adapted for receiving a cooperating engine element, a crankshaft, said structure provided with a crankshaft bearing positioned

intermediate a pair of adjacent cylinders, said bearing having a length greater than the distance between said cylinders and provided with recessed end portions constructed to provide clearance permitting axial assembly of the engine elements with said cylinders.

80

5. An engine structure having a cylinder adapted for receiving a cooperating engine element, a crankshaft, said structure provided with a crankshaft bearing located closely adjacent to the cylinder, said bearing having an arcuate recessed end portion adapted to provide clearance permitting axial assembly of said engine element with the cylinder.

85

6. A sleeve valve engine having a cylinder, sleeve valve means cooperatively associated with the cylinder, a crankshaft, said engine provided with a crankshaft bearing having a recessed portion to provide clearance permitting axial assembly of said sleeve valve means with said cylinder.

90

7. A sleeve valve engine having a cylinder, sleeve valve means cooperatively associated with the cylinder, a crankshaft, said engine provided with a crankshaft bearing having a recessed end portion to provide clearance permitting axial assembly of said sleeve valve means with said cylinder.

95

8. A sleeve valve engine having a cylinder, sleeve valve means cooperatively associated with the cylinder, a crankshaft, said engine provided with a crankshaft bearing having an arcuate recessed end portion to provide clearance permitting axial assembly of said sleeve valve means with said cylinder.

100

9. A sleeve valve engine having a plurality of cylinders, sleeve valve means cooperatively associated with said cylinders, a crankshaft, said engine provided with a crankshaft bearing positioned intermediate a pair of adjacent cylinders, said bearing having arcuate recessed end portions adapted to provide clearance permitting axial assembly of said sleeve valve means with the cylinders.

110

10. A sleeve valve engine having a cylinder, sleeve valve means cooperatively associated with said cylinder and consisting of a body portion and an enlarged collar portion adjacent the inner end of the sleeve valve means, a crankshaft, said engine provided with a crankshaft bearing having a recessed portion adapted to provide clearance with respect to the body portion of said sleeve valve means and said bearing, said enlarged collar portion having a cut-away portion whereby said sleeve valve means can be axially assembled with the cylinder.

120

11. A sleeve valve engine having a plurality of cylinders, sleeve valve means respectively cooperatively associated with an adjacent pair of said cylinders and each including a body portion and an enlarged collar portion adjacent the inner end thereof, a crankshaft, said engine provided with crankshaft bearings, one of said bearings located intermediate said adjacent cylinders having recessed end portions to provide clearance for assembly of said sleeve valve body portions.

130

12. The method of assembling sleeve valve means with a cylinder of an internal combustion engine having a crankshaft and a crankshaft bearing normally constructed to overlap the cylinder, which consists of axially introducing said sleeve into the cylinder by passing same by a recessed portion of the crankshaft bearing.

135

13. The method of assembling sleeve valve means with a cylinder of an internal combustion engine having a crankshaft and a crankshaft

145

150

bearing normally constructed to overlap the cylinder, which consists of axially introducing said sleeve into the cylinder by passing same by a recessed portion of the crankshaft bearing and partially rotating said sleeve valve means when clear of said bearing into a position for operative connection with a sleeve driving mechanism.

14. A sleeve valve engine having a cylinder, sleeve valve means cooperatively associated with said cylinder and consisting of a body portion and an enlarged collar portion adjacent the inner end of the sleeve valve means, a crankshaft, said engine provided with a crankshaft bearing having a recessed portion to provide clearance with respect to said sleeve body portion, a sleeve driving lug secured to said enlarged collar portion, said enlarged collar portion having a cut-away portion providing clearance with respect to the bearing thereby adapting the sleeve valve means for axial assembly with said cylinder and for partial rotation about its axis into an operative position when clear of said bearing.

15. An engine structure having a plurality of cylinders each adapted for receiving a cylindrical cooperating element, a crankshaft, said

structure provided with a crankshaft bearing positioned inwardly of and intermediate a pair of adjacent cylinders, said bearing having arcuate recessed end portions arranged substantially concentric with the cylinder to provide clearance permitting outward axial assembly of the cylindrical elements with said cylinders.

16. A sleeve valve engine having a cylinder, a sleeve valve associated therewith and consisting of a body portion and an enlarged collar portion adjacent the inner end of the sleeve valve, means operatively connected with the collar portion for imparting a combined reciprocating and oscillating movement to said sleeve valve for performing the usual valving functions of the engine, a crankshaft, said engine provided with a crankshaft bearing positioned inwardly of the engine cylinder and having a recessed portion adapted to provide clearance with respect to the body portion of said sleeve valve and said bearing, said enlarged collar portion having a cut-away portion whereby to permit outward axial assembly of the sleeve valve with the engine cylinder.
